UNITED STATES PATENT OFFICE.

WILLIAM B. HAYDEN, OF COLUMBUS, OHIO.

DESIGN FOR A HARNESS-BUCKLE.

SPECIFICATION forming part of Design No. 11,826, dated June 22, 1880.

Application filed May 12, 1880. Term of patent 3½ years.

To all whom it may concern:

Be it known that I, WILLIAM B. HAYDEN, a citizen of the United States, residing at Columbus, in the county of Franklin and State 5 of Ohio, have invented and produced a new and original Design for Harness-Buckles, of which the following is a specification.

My design consists in a buckle-frame slightly wider at the front than at the rear 10 end, having a cross-bar carrying a tongue, and curved sides, forming, with the rear portion, a flat seat, the front portion being curved upward from the sides, forming substantially an arch-shaped connecting-bar, which is curved 15 from its front to its rear edge, as more fully hereinafter specified.

The figure in the accompanying drawing represents a perspective view of the buckle.

The letter A indicates the frame of the 20 buckle, which is wider at its front than at its rear.

The rear portion of the buckle-frame is formed with a flat seat, B, from which the sides of the frame extend abruptly downward, 25 as at C, after which they curve forward toward the front edge of the buckle, as at c.

The lower edges of the sides are also symmetrically curved downward and upward, as at

d d', forming a depending rounded portion, d', from which the transverse cross-bar of the 30 buckle extends.

The upper surfaces of the side bars of the buckle-frame are gradually broadened laterally toward their front ends, as at f.

The front portion of the buckle-frame is secured abruptly upward, as at G, and gradually curved from side to side, forming substantially an arch-shaped bar, F, connecting the sides of the frame, which bar F is curved from its front to its rear edge. 35

The tongue H is formed with a double curve, 40 e e'.

What I claim is—

The design for a buckle, the same consisting of the frame A, wider at its front than at its 45 rear, the flat seat B, downward-projecting portions C, curved portions c, laterally-widened side bar, f, and arched connecting-bar F, all substantially as shown and described.

In testimony whereof I have hereunto set 50 my hand in the presence of the subscribing witnesses.

WILLIAM B. HAYDEN.
